Primary Examiner — Mary Shannon Malley*Assistant Examiner* — Olivia Aldin(74) *Attorney, Agent, or Firm* — RANKIN, HILL & CLARK LLP(57) **CLAIM**

The ornamental design for a washer, as shown and described.

DESCRIPTION

FIG. 1 is a top front right side perspective view of a washer showing my new design;

FIG. 2 is a bottom rear left side perspective view of FIG. 1; FIG. 3 is a front elevation view of FIG. 1;

FIG. 4 is a rear elevation view of FIG. 1;

FIG. 5 is a left side elevation view of FIG. 1;

FIG. 6 is a right side elevation view of FIG. 1;

FIG. 7 is a top plan view of FIG. 1; and,

FIG. 8 is a bottom plan view of FIG. 1.

The evenly spaced broken lines in the drawings depict portions of the washer that form no part of the claimed design. The dot dash lines form a boundary around claimed portions of the design and the dot dot dash lines form a boundary around claimed portions of the design.
